UNITED STATES PATENT OFFICE.

CHARLES E. SAGE, OF ROCHESTER, NEW YORK.

OIL-WELL CONTROLLER.

1,354,694.

Specification of Letters Patent.

Patented Oct. 5, 1920.

Application filed June 24, 1920. Serial No. 391,287.

To all whom it may concern:

Be it known that I, CHARLES E. SAGE, a citizen of the United States, and resident of Rochester, in the county of Monroe and 5 State of New York, have invented certain new and useful Improvements in Oil-Well Controllers, of which the following is a specification.

The present invention relates to oil well controllers and more particularly to the type in which a divided head is provided for ready attachment to the end of the well casing for the purpose of closing the casing quickly in the event of the striking of 10 a gusher, an object of this invention being to provide a simple and durable construction which may be quickly adjusted to effectively close the upper end of the casing tube.

To this and other ends, the invention consists of certain parts and combinations of parts all of which will be hereinafter described, the novel features being pointed out in the appended claims.

In the drawings:

25 Fig. 1 is a view partially in section showing the casing head in elevation connected to the upper end of a casing tube;

Fig. 2 is a vertical section on the line 2—2, Fig. 1;

30 Fig. 3 is a plan view of the casing head with parts in section;

Fig. 4 is a section on the line 4—4, Fig. 2;

Fig. 5 is a plan view partially in section of the packing ring; and

35 Fig. 6 is an edge view of the packing ring.

Referring more particularly to the drawings, 1 indicates the casing tube which is externally threaded at 2 at its upper end. 40 On this externally threaded end is arranged a packing ring 3 preferably formed of soft metal such as soft steel and having its periphery beveled at opposite sides at 4. This ring is internally threaded at 5 to engage the 45 external threads of the casing tube. It is preferred also to make this ring in two sections, the sections being preferably connected together by two links 6, the links being secured to the ring sections at 7 and being received in the pockets 8 formed in the 50 periphery of the ring adjacent the joints between the sections.

The upper end of the casing tube is preferably held between two I beams 9 which 55 have blocks 10 bolted at 11 to their opposed faces, the opposed faces of the blocks be-

ing curved and engaging the opposite sides of the casing tube 1. These blocks are removable to permit casing tubes of different diameters to be clamped. Tie-bolts 12 secure the I-beams together and in firm engagement with the casing tube 1, the outer tie-bolts 12 having tubes 13 surrounding them and acting to space the outer ends of the I beams apart. The casing tube with 60 the packing ring projects above these I beams.

The casing head is formed, in this instance, of two sections 14 and 15, the head being divided in the direction of the casing 65 2 to provide such sections. When the sections are associated together, a passageway through the head is provided which extends in the direction of the longitudinal axis of the casing 1. The sections are preferably 70 held together by bolts or rods 16 which are threaded at opposite ends as at 17 and 18. The threaded ends 17 are secured in the member 14 so that the bolts or rods project from said member and act as guides for the 75 member 15. Nuts 19 are secured on these rods and serve to hold the member 15 to the member 14. During the drilling of the well, the members 14 and 15 are removed from the 80 beams or are separated and are supported 85 on the I beams 9, such I beams acting as guides in order to direct the members 14 and 15 into coöperation. This guiding is preferably secured by providing the lower 90 ends of the casing members 14 and 15 90 with guiding hooks 20 at the lower portions of said members, these guiding hooks traveling on the uppermost flanges of the I-beams. The inner faces of the members adjacent their guiding hooks 95 are provided with groove segments 21 which when together form an annular groove at the lower end of the passageway through the casing head. The upper and lower walls of this groove are beveled and coöperate with 100 the beveled edges 4 of the ring 3 in order that when the sections are drawn together, the perimeter of the ring 3 will be compressed and a tight joint between the ring and the casing head will be established. 105 The member 15 may be provided with a lateral port 22 from which a piping may lead to conduct oil to any suitable point, whereas the member 14 is provided with a valve member 23 operable through a stem 24 in a 110 well known manner. This valve member may be moved to a position where the pas-

sageway through the casing head will be opened and may also be moved to coöperate with divided valve seats 25 formed on the two casing sections 14 and 15.

5 During drilling the members 14 and 15 may either be supported in separated positions on the I beams 9 or may be removed therefrom. The dividing packing ring is formed with an external diameter corresponding to the internal diameter of the casing head members while its central opening has a diameter corresponding to the diameter of the casing. It is apparent this construction permits the use of the head 10 with casing tubes of different diameters merely by using the packing rings which have central openings corresponding to the diameter of the casing tubing. The packing ring may either be secured to the casing 15 tubing during the drilling or may be separated from the casing tubing to be fitted thereto when a gusher is struck.

In attaching the casing head, the casing members are moved together on the I beams 25 9, the members 15 being guided toward the member 14 by the rods or bolts 16. The nuts 19 are then quickly secured to the screw threaded ends 18 of the bolts so as to draw the members 14 and 15 together. 30 As these members are brought together, the packing ring 3 has its periphery brought in firm engagement with the walls of the members 14 and 15 so that a liquid tight joint is provided between the casing tube 35 and the casing head. After the casing members are secured together, the valve 23 is closed, thus directing the oil through the port 22. If it is desired later, a pipe may be connected to the flanged upper end 26 40 of the casing head and the oil may be also taken from the head at this point.

What I claim as my invention and desire to secure by Letters Patent is:

1. An oil well controller comprising, in 45 combination with a well casing, a pair of beams supported on opposite sides of the casing below the upper ends thereof, blocks secured to the inner faces of said beams and

having their inner ends engaging the well casing on opposite sides, tie bolts connecting said beams together, and a casing head having a passageway in line with the casing and divided longitudinally of the casing into two parts, each of which is guided on the beams. 50

2. An oil well controller comprising, in combination with a well casing, a pair of beams supported on opposite sides of the casing below the upper end thereof, means for tying and spacing said beams, a casing 60 head having a passageway in line with the casing and divided longitudinally of the casing into two sections each of which has its lower end guided on the two beams, and a packing ring secured to the projecting 65 portion of the well casing and adapted to be engaged by the two sections of the casing head.

3. An oil well controller comprising, in combination with a well casing, a pair of 70 beams supported on opposite sides of the casing below the upper end thereof, blocks secured to opposed faces of said beams and having their free ends engaging the well casing below the upper end thereof, tie bolts 75 connecting the beams, a casing head having a passageway in line with the well casing, said head being divided longitudinally of the well casing into two sections, each of which has its lower end guided on the two 80 beams, and a packing ring interposed between the projecting end of the well casing and the casing head.

4. An oil well controller comprising, in combination with a well casing, a packing 85 ring of soft metal having screw threaded engagement with the upper end of the well casing, and a casing head divided in the direction of the length of the well casing and having a passageway in line with said 90 well casing with an internal groove in the walls thereof formed to compress the perimeter of the packing ring when the two members of the casing head are secured together.

CHARLES E. SAGE.
